UNITED STATES PATENT OFFICE.

GARTH G. GILPIN, OF RIVERSIDE, ILLINOIS, ASSIGNOR TO WALTER P. MURPHY, OF CHICAGO, ILLINOIS.

RELEASE RIGGING.

Application filed September 19, 1921. Serial No. 501,579.

To all whom it may concern:

Be it known that I, GARTH G. GILPIN, a citizen of the United States, residing at Riverside, in the county of Cook and State 5 of Illinois, have invented new and useful Improvements in Release Rigging, of which the following is a specification.

This invention relates to improvements in release rigging for car couplers and more 10 particularly to the construction of the car coupler lock pin lifting link.

Before the ruling of the American Railroad Association against the use of a chain and clevis for lifting the coupler lock pin 15 a type of release rigging comprising a rotatable bar having a depending handle on the outer end and a crank arm extending over the coupler at the other end mounted on the crank arm end with a chain and clevis 20 connecting the end of the crank arm and the lock pin had been in extensive use. An object of this invention is to provide a link that can be used with this type of operating rod and answer the requirements of the 25 American Railroad Association interchange rules and rules covering new equipment. In the chain and clevis type the crank arm was provided with an eye in line with and above the eye in the lock pin and it is another object of this invention to provide a pin lifter 30 link that is flexible in all directions and after once installed cannot become detached in service and which will engage in the eyes of the crank arm and lock pin respectively. 35 While the preferred forms of this invention are illustrated upon the accompanying sheets of drawing, yet it is understood that minor detail changes may be made without departing from the scope thereof.

40 In the drawing Fig. 1 is a diagrammatical view of this improved pin lifter link in side elevation as applied to a car illustrating the end of the lifting or uncoupling movement in dotted lines.

45 Fig. 2 is an enlarged detail view in side elevation of one element of the link.

Fig. 3 is an enlarged detail view in front elevation of Fig. 2.

50 Fig. 4 is an enlarged detail view in side elevation of the link applied to the crank arm and coupler pin in normal position.

Fig. 5 is a similar view in front elevation of Fig. 4.

As illustrated in Fig. 1—1 is the end sill, 2 the striking casting, 3 the coupler head 55 and 4 the car end, all of which are of usual construction; 5 is the rotatable operating rod of the release rigging mounted in brackets 6 on the end sill having a vertically depending handle 7 on the outer end and a horizontally 60 extending crank arm 8 on the other end terminating in an enlarged eye over the car coupler lock pin, which construction is of a well known type and has gone into general use. 65

The improved pin lifting link comprises two elements 10 and 11 which are provided with interlocking eyes 12 and 13 formed by bending the adjacent ends one about the other in the manner shown and which are of sufficient size to allow of free play of each 70 element in the other. The opposite or free ends of the elements are each provided with what may be called pig tails 14 and 15. As illustrated, each of the elements are 75 formed from round bars with shanks 16 and 17 extending from the eyes 12 and 13. The pig tails are formed in the free ends by bending the shanks in the form of helices or spiral curves with the ends 18 and 19 80 terminating below and beyond planes at right angles to the center lines of the shanks passing through the center of the helices or spirals, and with the diameter of the helices or spirals and the distance between the body 85 of the shank and the convolutions 20 and 21 of the pig tails sufficiently great to pass through the eye and receive the body of the crank arm or coupler lock pin. It is preferable to form one of the interlocking eyes in 90 the plane passing through the center of the shank and center of the helices or spirals and the other at right angles to such plane, as shown in Fig. 4.

When this improved link is to be used it 95 is preferable to apply one element to the eye in the crank arm by inserting the end of one pig tail in the eye and rotating it about the crank arm end until it is engaged therewith. Then to apply the link to the coupler pin 100 22 before the rod is attached to the car the end of the other pig tail is inserted in the

eye 23 of the lock pin and rotated thereabout until engaged and the operating rod then mounted in its brackets on the end sill.

As seen in Figs. 1, 4 and 5 the link positively engages in the eyes of the crank arm and car coupler lock pin and cannot be detached without first removing the operating rod from the car body. The link is flexible so as to allow of longitudinal movement of the coupler in draft and buffing and latitudinal movement of the coupler during the swinging movements of the car in service or going around curves without affecting its operativeness. An upward movement of the crank arm straightens out the link with its elements in tension upon the lock pin and a further upward movement will unlock the coupler and when the lock is in said lock set position and the handle released the crank arm can return to its normal horizontal position.

It will be noted that the helical or spiral ends of the two links are identical but that the two links are so formed that when connected together it is impossible to connect the upper link to the operating rod and the lower link to the coupler eye by a rotative motion of the connected links and vice versa, it is impossible to disjoin the links from said operating rod and coupler eye by a rotative motion. A rotative motion of the two links secured together would thread one link into its adjacent eye and the other link out of its adjacent eye.

This pin lifting link is a cheap, easily constructed effective link answering the American Railroad Association rules and may be applied to new or old cars in place of the

chain and clevis construction between the operating rod crank arm and coupler lock pin.

What I claim is:

1. In a release rigging for a car coupler comprising an operating rod having a horizontally disposed eye, a coupler lock pin having a horizontally disposed eye, and a connector operatively connecting said eyes composed of two links flexibly connected at their adjacent ends, each link formed at its opposite end into a spiral hook, said spiral hooks so positioned that a rotative motion of the two connected links would thread one link into its adjacent eye and the other link out of its adjacent eye.

2. In a release rigging for a car coupler comprising an operating rod having a horizontally disposed eye, a coupler lock pin having a horizontally disposed eye, and a connector operatively connecting said eyes composed of two links flexibly connected at their adjacent ends, the upper part of the upper link and the lower part of the lower link each having a bend extended to form a complete loop, the smallest overall dimension of the loop being greater than any dimension of the eye of the member to which it is connected whereby said link can only be engaged or disengaged with said member by a pivotal movement about an axis substantially perpendicular to the plane of the loop, said loops so positioned that a rotative motion of the two connected links would thread one link into its adjacent eye and the other link out of its adjacent eye.

GARTH G. GILPIN.
